THEODORE BODDE, OF NIAGARA FALLS, NEW YORK, ASSIGNOR TO THE REGAN SAFETY DEVICES COMPANY, INC., OF NEW YORK, N. Y., A CORPORATION OF NEW YORK.

TRAIN-CONTROL SYSTEM.

Application filed November 13, 1923. Serial No. 674,505.

This invention relates to a train control system and more particularly to a system for automatically controlling the movement of cars, trains or the like in response to varying track or roadside conditions; and has special reference to the provision of an improved system of the type set forth in my copending application for train control system, Ser. No. 566,565, filed June 7, 1922.

10 The principal objects of the present invention comprehend the provision of a novel train control system in which the companion train and track apparatus are correlated to affect a very sensitive inertialess apparatus 15 adaptable for instantaneous operation and instant response to roadside conditions especially serviceable for fast moving vehicles and trains; the more specific provision of an inductive train control system in which an electron discharge device forming part of the vehicle carried mechanism is magnetically influenced by roadside mechanism for producing any of three indications or train control effects in response to different roadside conditions such as "clear", "caution" and "danger" conditions; the further provision of a train control system of this nature in which the magnetically controlled electron discharge device controls the train mechanism 20 to place the same under a speed restriction; and the further provision of vehicle carried mechanism controlled by a magnetically operable electron discharge device for producing graduated or progressively limiting 25 speed control of trains.

30 35

To the accomplishment of the foregoing and such other objects as may hereinafter appear, my invention consists in the elements and their relation one to the other as 40 hereinafter particularly described and sought to be defined in the claims, reference being had to the accompanying drawings which show preferred embodiments of my invention, and in which:

45 Fig. 1 is a diagrammatic view of the vehicle carried apparatus of my train control system,

Fig. 1^a is a view of the roadside apparatus on a reduced scale,

50 Fig. 2 is a diagrammatic view of magnetic elements forming a part of the roadside apparatus and showing the method of electrically connecting the same,

Figs. 3 and 3^a are views of vehicle carried and roadside apparatus respectively employed for affording curve protection, 65

Fig. 4 is a diagrammatic view of a modification of roadside apparatus employed for affording curve protection, and

Fig. 5 is a graphical view of the characteristics and operation of the vehicle carried apparatus.

Before describing the present exemplification of the invention I will briefly premise that in one of its broad aspects my invention 65 comprehends the provision of a train control system of the non-contact or induction type in which a vehicle carried mechanism is controlled by the cooperation of vehicle carried electron discharge means and roadside means 70 which magnetically influences the electron discharge means in the movement of a vehicle over a roadbed for producing any of three different indications in the vehicle carried mechanism in response to changes in 75 traffic conditions. More specifically, by my present invention a vehicle carried electron discharge device is magnetically operated by roadside mechanism to produce "clear", "caution" and "danger" train indications in 80 response to and in accordance with corresponding roadside conditions.

The mechanism which I prefer to provide in carrying out this object of the invention comprises generally an indicating means 85 generally designated as I which is selectively operable into any of a plurality of positions for producing the different train indications, the operation of the said indicating means from "clear" to "caution" and "danger" positions being controlled by a controlling mechanism generally designated as C and the restoration of the indicating means to a "clear" position being effected 95 by a restoring mechanism generally designated as R, the controlling and restoring mechanisms being operated and controlled by the electron discharge device in the form of a magnetron M which is magnetically influenced by roadside mechanism to produce the selective operations of the indicating means I.

In the present embodiment of the invention, the operation of the indicating means I controls the movement of the train, the control being preferably such that with a 100 105

- "clear" indication the train will be permitted to proceed at a maximum or unlimited speed, and with a "caution" indication the train will be placed under a speed restrictive control, and with a "danger" indication the train will be operated to bring the same to a low speed or to a halt. To these ends the indication means I controls a plurality of circuits for operating a magnet 10 which 10 controls a brake valve mechanism 11 and for placing the brake magnet under the control of a speed circuit controller 12, which latter is connected to be operated by the running gear of the vehicle. These controlled circuits include a "normal" or "clear" circuit generally designated as *a* and comprising the tapered contact element 13 forming part of the indication means I, the conductor 14, the battery 15, magnet winding 10, conductors 16 and 17, and a contact element 18 fixed to an insulated plunger bar 19 and normally arranged for engagement with the contact element 13 as shown in Fig. 1 of the drawings. Under "clear" running conditions this circuit is closed for energizing the electromagnet 10, the energization of this electromagnet permitting the train to proceed at speed.
- The controlled circuits further include one or a plurality of "caution" circuits designed to place the train under a restrictive speed control in response to "caution" traffic conditions, and in the preferred embodiment of the invention the "caution" circuits are constructed so that when operated in succession a graduated speed control is made effective. These "caution" circuits generally designated as *b*, *b'* and *b''* are rendered operative when the indication means I is moved from the position shown in Fig. 1 to positions where the contact element 13 engages in succession the contact elements 20, 21 and 22 fixed in spaced relation to the plunger bar 19. The engagement of contact 13 with contact 20 closes the "caution" circuit *b*, this circuit comprising the contact 13, conductor 14, battery 15, magnet 10, conductors 16 and 23, circuit controller 12, contact 24 closed when the speed of the train does not exceed a permissive maximum speed such as 50 miles an hour under "caution" conditions, conductor 25 and contact 20, this circuit being therefore closed to energize the magnet 10 to permit movement of the train at or below the maximum permissive speed under a "caution" operation. Similarly when the contact 13 moves into engagement with the contact 21, the circuit *b'* which includes a second contact 24' and the conductor 25' is operated, the contact 24' being arranged for closing this circuit when the speed of the train does not exceed a medium speed, such for example as 35 miles an hour, this circuit being therefore designed to permit movement of the train at a speed not

exceeding the medium permissive speed under a second "caution" operation with the contacts 13 and 21 in engagement as described. When the contact 13 moves into engagement with the contact 22, the circuit *b''* is operated, this circuit including the contact 24'' and the conductor 25'', the contact 24'' being arranged to be closed by the speed circuit controller 12 when the speed of the train does not exceed a low permissive speed, this circuit therefore being closed to energize the magnet 10 under a third "caution" operation. As will be described further in detail hereinafter, the plunger bar 19 is operated under "caution" track conditions to effect the movement of the contact element 13 into successive engagement with the contact elements 20, 21 and 22 as the train proceeds along the "caution" block, and it will therefore be evident that with this operation the train will be placed under progressive or tapered speed restrictions as the train approaches the exit end of the "caution" block.

The indication means I is also operable in response to a "danger" condition to a position where the contact element 13 lies below the contact element 22 and when so operated it will be apparent that the "clear" and "caution" circuits *a*, *b*, *b'* and *b''* are all open and the valve controlling magnet 10 consequently deenergized to bring the train to a halt.

For controlling the movement of the indication means I in one direction, the controlling mechanism C heretofore referred to is provided, this controlling mechanism comprising a plunger armature 26 carrying the plunger bar 19 which is operable by a permanent magnet 27 and an electromagnet 28 for movement in opposite directions, the said electromagnet 28 being controlled by a circuit generally designated as *c* comprising battery 29, conductor 30, electromagnet 28, conductors 31 and 32, a front contact 33, contact 34 controlled by relay 35, and conductor 36. When the front contact 33 is closed, this circuit *c* energizes the electromagnet 28 and the attraction of the same on the plunger 26 exceeding that of the magnet 27, the plunger armature 26 moves to the right to effect the interception of and engagement with the contact element 13 by the contact elements on the bar 19, and when this circuit is opened at the front contact 33 the electromagnet will be deenergized to permit the attraction of the armature 26 by the permanent magnet 27 to effect movement of the plunger armature to the left so as to permit disengagement of the contact element 13 and to permit descending movement of the indication means I.

For restoring the indication means I to the position shown in Fig. 1 after the same has been moved to descended position, the

restoring mechanism R heretofore referred to is provided, the said restoring mechanism comprising an electromagnet 37 operated by a restoring means generally designated as 38, the electromagnet being controlled directly by a circuit generally designated as d comprising the battery 29, conductor 39, an armature bar 40 normally lying in the full line position x shown in the figure and 10 movable in opposite directions to the dotted line positions y and z , a contact element 41 on the said armature bar, a movable contact element 42 normally held against a stop 43 by means of a spring 44, conductor 15 45, an electromagnet 46, conductor 47, the electromagnet 37, conductor 48, a back contact 49, contact 34 in dotted line position, and conductor 36. This circuit d is normally open as shown at the contact element 42 20 and back contact 49 so that the indication means I which is provided with an extension 50 forming a plunger for the electromagnet 37 is free to descend when the control means C is operated. When, however, the relay 35 25 is deenergized to permit the closing of the contact 49 and the armature bar 40 is moved to the dotted line position y for engagement with the contact element 42, the circuit d will be closed to energize the electromagnet 37 and move the indication means I to the 30 ascended or restored position.

The operations of the controlling mechanism C and restoring mechanism R to produce the different train indications are controlled by the electron discharge device M heretofore referred to, this device comprising a magnetically controlled electron discharge means or magnetron consisting of an evacuated vessel 51 provided preferably 35 with the straight filament cathode 52 and a cylindrical anode 53 arranged symmetrically about the cathode, the cathode being heated to incandescence by a glow circuit comprising the battery 54, conductor 55, the filament 52 and conductor 56, the cathode and anode being connected to control a circuit generally designated as e , which circuit comprises a battery 57, a solenoid 58, a conductor 59 connected to the anode 53, cathode 40 52, conductor 60, the relay magnet 35 heretofore mentioned, and the conductor 61. This controlled output circuit of the magnetron is normally energized with the magnetron open as will be presently described 45 55 to energize the relay magnet 35, and when the magnetron is closed this circuit will be deenergized to effect the deenergization of the magnet 35.

For controlling the magnetron M to close 60 and reopen the same, I provide means for creating controlling magnetic fields influencing the magnetron, the said means in the present construction comprising the solenoid 58 referred to and a permanent magnet 62, the solenoid for purposes of clarity of 65

illustration being shown in the drawings as arranged to the side of the vessel 51, it being understood however that the actual construction comprises a symmetrical arrangement of the solenoid and the permanent magnet, the solenoid being wound about and arranged coaxially with the anode and cathode of the electron tube.

As is known, in the absence of any magnetic influence on the electron discharge device or magnetron M, the same will be open and a current will flow through the controlled circuit e for energizing the said circuit to effect the operation of the relay 35. It is also known that when the magnetron 80 M is subjected to the influence of a magnetic field above a predetermined or critical magnitude, the electron flow between the cathode and anode will be interrupted for closing the magnetron and deenergizing the 85 relay magnet 35. This phenomenon is graphically illustrated in Fig. 5 of the drawings, the figure representing the operating characteristics of the magnetron under the influence of a magnetic field, the 90 strength of the magnetic field being represented by the abscissae and the strength of the current in the output or controlled circuit by the ordinates, the curve EDAB depicting the characteristics of the magnetron 95 and controlled circuit. If the strength of the magnetic field influencing the magnetron is less than the abscissa represented as FD, the electrons impelled from the cathode impinge uninterruptedly upon the anode, and 100 the current in the controlled circuit e will be a maximum as represented by the ordinate XE. If, however, the strength of the magnetic field exceeds the critical value represented by D, the electrons will be diverted and 105 prevented from reaching the anode 53 and the current in the output or controlled circuit e will suddenly fall without lag or inertia to a value as represented by the part of the curve AB. From this it will be seen that 110 the magnetron may be controlled by controlling in a predetermined manner the magnetic influence to which it is subjected.

For controlling the operation of the magnetron and the condition of the output circuit in accordance with my invention, I provide means for producing opposed magnetic fields influencing the magnetron, the said opposed magnetic fields having a given resultant magnitude, which magnitude is selectively changed and re-established to produce different conditions of operation. It is to this end that the solenoid 58 and permanent magnet 62 heretofore referred to are provided, the solenoid 58 being so wound as to 125 produce a magnetic field indicated by the arrow in Fig. 1 in opposition to the magnetic field of the permanent magnet 62, the strength of the opposing magnetic fields being so predetermined that the magnetic field 130

of the solenoid 58 when acting alone is effective for establishing one condition of operation and the strength of the resultant of both magnetic fields acting in opposition is effective for producing a different condition of operation.

These predetermined magnitudes are graphically depicted in Fig. 5 of the drawings, the strength of the magnetic field due to the magnet 62 being indicated by the arrowed line M' , the value of this field being greater than the critical value of the curve EDAB, this magnetic field being therefore sufficient when acting alone to close the magnetron and deenergize the controlled circuit, and the strength of the opposing magnetic field produced by the solenoid 58 being indicated by the opposing arrowed line O, the inter-reaction of the fields M' and O being such as to produce a resultant field indicated by the arrowed line R' , this resultant being of less value than the critical value of the curve, and being insufficient to disturb the open magnetron M and the energized relay circuit e , the value of the current in the circuit being represented by the ordinate drawn to the asterisk on the curve in Fig. 5 corresponding to the abscissa R' .

For producing the different train indications, the magnetron M is operated by a roadside mechanism which is designed to magnetically influence the magnetron M and to modify and re-establish the resultant magnetic field thereof in predetermined manners and preferably in at least three different ways to produce the "clear", "caution" and "danger" train indications in response to the corresponding traffic conditions. Referring now to Fig. 1^a of the drawings, I show a layout of roadside apparatus for three successive blocks X, Y and Z, with a vehicle 63 occupying block Z and being shown as moving towards the right, the blocks being insulated from one another by insulating one of the rails r at 64, 64, the other rail r being preferably made continuous. To provide for progressive speed control each of the blocks is subdivided into insulated sections n, n, n , insulated from each other as at 65, 65, block Y being shown subdivided into five sections so as to produce four control stations therein. Each block is provided with a track relay designated as 66 with an exponent corresponding to the block, the relay being connected across the rails at the entrant end of the block as shown, each relay controlling the operation of a circuit controller generally designated as 67 with an exponent corresponding to the block, the circuit controller governing the direction of current supplied to the block arranged to the rear of the controlling relay. The circuit controlling means for the block Y, for example, comprises the contact elements 68 and 69 connected to a battery 70 by means

of the conductor 71, conductor 72 and resistance 73, the contact elements 68 and 69 being movable from the position shown in the figure in which it engages the back contacts 74 and 75 to a position in which the front contacts 76 and 77 are engaged, the said front and back contacts being connected to the opposite rails by means of conductors 78, 79 and 80, the construction being such that movement of the contact elements from one position to the other will reverse the direction of current fed to the rails r by the battery 70.

Under "clear" roadside conditions as shown for the block X, the relay 66^x is energized to operate the circuit controller 67^x to feed current of a given direction into the rails and to the relay at the entrant end of the said block X. Under "caution" roadside conditions as shown for block Y with a train occupying block Z, the relay 66^z is shunted and deenergized and the circuit controller 67^z is operated to feed current to the rails r and the relay 66^y having a direction opposite to the said given direction. In a "danger" block the vehicle 63 shunts the current so that the rail sections to the rear of the vehicle in the same block therewith receive no current.

For producing the magnetic fields for influencing the magnetron M , the roadside mechanism includes the provision of a plurality of magnetic elements connected to receive current from the rails, the magnetic elements having changeable polarities so as to differently influence the magnetron under different roadside conditions. To effect at least three different train indications, I provide a plurality of sets of magnetic elements spacedly arranged on the roadbed, each set preferably consisting of three magnets having a given relative polarity arrangement or combination, which polarity combination may be changed in at least three different ways when traffic conditions are altered. Preferably the three magnets comprise a permanent magnet and two electromagnets, the electromagnets being connected across the rail sections n , and referring to Fig. 1^a, block Y, a set comprises the permanent magnet 81 and two electromagnets 82 and 83 connected across sections n, n , the permanent magnet 81 being vertical with the North Pole at the top and the electromagnets 82 and 83 being wound in opposite directions so as to present differing polarities at the top for influencing the magnetron.

In Fig. 2 I show this arrangement diagrammatically, and for convenience of illustration I show the magnets arranged horizontally, although it will be understood that these magnets are in vertical position with the top poles adjacent the magnetron which is moved thereover. It will be understood from this construction that the polarities of

the electromagnets 82 and 83 are reversed when the direction of current in the rails is reversed, and that more specifically under "clear" roadside conditions, as in that part 5 of the block Z in advance of the vehicle 63, the polarity combination influencing the magnetron is NSN, and under "caution" roadside conditions, as in block Y, the polarity combination for the first three control 10 stations is NNS, and under "danger" roadside conditions, as in that part of the block to the rear of vehicle 63, the polarity combination is NOO, the latter representing that the two electromagnets have been deenergized. The strength of the magnets of the 15 roadside mechanism is so chosen that the magnetic field, designated for convenience as N, aids the magnetic field of the permanent magnet 62 and opposes that of the solenoid 58, the influence on the magnetron being such that the effect of the opposing magnetic field is neutralized so that the main field M' alone is active for closing the magnetron and deenergizing the relay circuit, 20 and the magnetic field designated as S opposes the magnetic field of the permanent magnet 62, the influence of the magnetron being such that the main field M' is reduced to a value below the critical value of the 25 curve EDAB, Fig. 5, so that the magnetron is reclosed.

It will be noted that although the influence of the track magnet pole N on the magnetron is but momentary in the passage of 30 the magnetron along the roadbed, the deenergization of the controlled circuit *e* when the magnetron is closed deenergizes the solenoid 58 and eliminates the opposing magnetic field thereof so that a sustained deenergization of the relay circuit is effected by 35 such momentary influence; and it will be further seen that although the influence of the magnet pole S is also but momentary, the reopening of the magnetron energizes 40 the controlled circuit and the solenoid 58 so that the opposing field of the solenoid 58 is re-created or re-established to maintain or cause a sustained opening of the magnetron 45 and energization of the controlled circuit.

The operation of the system under "clear", "caution" and "danger" conditions will now be described. When the roadside condition is "clear" the vehicle moves over the magnet combination NSN and the magnetron 50 M is influenced by three successive impulses to effect a closing, reopening and a reclosing of the same. The first impulse which produces a closing of the magnetron causes the opening of the circuit *e* and the retreat of the plunger 26 under the influence of the magnet 27 releasing the indication means I. The movement of the contact element 34 also opens another circuit *f*, which 55 comprises the battery 29, conductor 39, ar-

mature bar 40, contact 41, a contact element 84 normally held against the stop 85 by a spring 86, conductor 87, electromagnet 88, conductor 89, conductor 32, front contact 33, contact element 34 and conductor 36, this circuit being normally closed to hold the 60 armature bar 40 in the neutral full line position shown in the figure. Normally the attraction of the bar 40 by the magnet 90 is insufficient to overcome the attraction of the bar 40 by the electromagnet 88 when the latter is energized. When the circuit *f* is opened at the contact 33 upon the closing of the magnetron, the electromagnet 88 is deenergized and the bar 40 under the influence of the permanent magnet 90 moves to the dotted line position *z*. When the magnetron is subjected to the second and reopening impulse, the relay 35 is energized to attract the contact element 34, and this effects the momentary closing of the circuit *e* which moves the armature plunger 26 to a position to intercept momentarily the indication means I. The closing of the front contact 33 under this impulse also reenergizes the circuit *f* which remains closed at the contact element 84 65 (dotted line position *z*) so that the electromagnet 88 is reenergized to attract the armature bar 40. This armature bar moves from the position *z*, and due to its inertia moves past the position *x* to the position *y* 70 for engaging the contact element 42. Since, however, the second impulse closes the front contact 33, the movement of the bar 40 to close the contact 42 has at this moment no effect. The third and reclosing impulse due to the third magnet N causes at this moment however a deenergizing of the relay 35 and a 75 closing of the back contact 49 of the circuit *d*, and since this circuit *d* is now closed at both contacts 42 and 49, the restoring magnet 37 is energized to effect the ascending movement of the indication means I and the magnet 46 is energized to hold the bar 40 in position *y*. The indication means is provided with a contact element 91 which is arranged 80 to engage a contact 92 when the indication means is moved to the fully ascended position, these contacts being arranged to close a circuit *g* comprising the battery 57, the conductor 93, a resistance 94, contact 92, 85 contact element 91 which is connected to conductor 95, and magnetron solenoid 58, the closing of this circuit in energizing the solenoid 58 effecting the re-creation of the opposing magnetic field of the solenoid and 90 the reopening of the magnetron. When the magnetron is thus reopened by these vehicle means, the circuit *e* is reenergized to move the plunger armature 26 to the position shown in Fig 1 of the drawings so 95 that when the electromagnet 37 is deenergized by the simultaneous opening of the circuit *d*, the indication means I will drop

into engagement with contact 18 to close the normal brake circuit *a*. These operations take place with rapid succession and test the integrity of the vehicle carried mechanism at each "clear" control station, the operations being produced without effecting the application of the brakes.

In a "caution" block such as Y, the vehicle moves over the magnet combination NNS 10 and the magnetron M is influenced by three successive impulses, the first two of which produce a closing of the magnetron, and the third of which produces a reopening of the magnetron. As already described, when the 15 magnetron is closed and reopened, the circuit *c* is first opened to deenergize the electromagnet 28 and permit the descending movement of the indication means I, the circuit *c* being, however, reclosed to effect the 20 reenergization of the electromagnet 28 and the movement of the plunger 26 to the right to cause the intercepting of the indication means I by the contact element 20. To prevent the too rapid movement of the indication 25 means I during the interval of deenergization and reenergization of the electromagnet 28, retarding means may be provided and preferably the plunger 50 is made to fit snugly in the electromagnet 37, the latter 30 being also provided with a loosely mounted disk 97 at its upper end. When the magnetron is closed and reopened under caution conditions, the circuit *f* is first deenergized and then reenergized, with the result that 35 the bar 40 first moves to the position *z* and then is actuated to the position *y*, the closing of the contact 42 in the latter position being, however, ineffectual for closing the circuit *d* of the restoring mechanism, since the reopening 40 of the magnetron causes the making of the front contact 33 of the relay 35 and the breaking of the back contact 49. The armature bar 40 under the influence of the magnet 90 is actuated to the return position 45 *x*, and in this position the circuit *f* is closed for energizing the magnet 88, the latter attracting the armature 40 to the "normal" or "neutral" position.

As the train advances in the "caution" 50 block, the magnetron is brought under the influence of the second set of magnets and the closing and reopening operation of the magnetron is repeated, with the result that the indication means I is permitted to move 55 another increment of distance to a position intercepted by the contact 21 for closing the "caution" circuit *b'*. As the vehicle advances still further in the "caution" block, the magnetron is subjected to the influence 60 of a third set of magnets and the closing and reopening of the magnetron again takes place, with the result that the indication means I moves in a position to be intercepted by the contact 22 for the closing of the cir-

cuit *b*. Thus the magnetron is operated to 65 produce progressive speed limiting restrictions as the vehicle approaches the "danger" block.

When the vehicle reaches the last control station in the "caution" block, the indication 70 means I will move beyond the contact 22 to open all the train control circuits and bring the vehicle to a halt. In the preferred construction the last set of magnetic elements in the "caution" block differs from the preceding sets in that the electromagnets 82' and 83' are arranged in advance of the permanent magnet 81', the polarity combination being under "caution" conditions SNN as seen in Fig. 1^a. With this combination 80 the magnetron is closed so as to assure the production of a stop indication or effect on the train mechanism.

The "stop" effect is also produced under "danger" conditions by the movement of the 85 vehicle in a "danger" block with the magnetron influenced by the magnet combination NOO, as shown in block Z. With this magnet combination the magnetron is closed, causing the deenergization of the electromagnet *c* and the movement of the plunger 26 to the left, the indication means I being then permitted to move to its fully descended position for opening the vehicle "clear" and "caution" circuits. 95

After a vehicle stop has been produced, the indication means I may be manually restored by moving the plunger 50 upwardly to close the circuit *g*. If it is preferred to mount the restoring magnet 37 and the indication means I in the cab of the vehicle, this manual restoration is eliminated and means provided which is manually operable for modifying the "stop" effect and substituting therefor a restrictive speed effect, the said 105 means comprising a circuit *h* which consists of an electromagnet 98, conductor 99 connected to the conductor 25², contact 24², circuit controller 12, conductor 23, magnet 10, battery 15, conductor 14, contact element 13, 110 a contact element 100 arranged to intercept the contact element 13, conductor 101, contact 102 connected to be operated by a push key 103, front contact 104 and conductor 105. When the indication means I descends 115 to a position where contact element 13 engages contact element 100, this circuit may be closed by the operation of the push key 102, the electromagnet 98 holding this circuit closed so that the brake valve magnet 120 10 is placed under the control of the low restrictive speed. For the purpose of informing the engineman when this circuit is in a condition to be closed, there is provided the signal element 106 connected by means of conductor 107 to a back contact 108, the signal element being also connected to one end 125 of the battery 15 by means of the conductor

109. With this arrangement, it will be evident that when engagement between the contact elements 13 and 100 takes place, the signal circuit will be energized.
- 5 Referring now to Figs. 3 and 3^a of the drawings, I show means for independently controlling the vehicle carried mechanism at permanent hazards along the roadside, such as at curves, crossings, tunnels or the like.
- 10 The vehicle carried means for such purpose may comprise an inductor 110 connected to the output circuit *e* of the magnetron *M* and arranged in series with the solenoid 58 and the battery 57. The roadside mechanism 15 may comprise an inductor or magnet 111 arranged between the rails *r*, *r* and adjacent one of said rails so as to be out of alinement with the magnet combination NSN so as not to directly influence the magnetron *M*. In the passage of the inductor 110 over the magnet 111 a current cycle is induced in the output circuit *e* the direction of the last phase of which is such as to oppose the current in the solenoid 58, the value of which 20 current is a function of the speed of movement of the train. If the train exceeds a predetermined speed, this induced current is sufficient to produce a magnetic field in opposition to that existing in the solenoid 58 25 as indicated by the opposed arrows in Fig. 3 and sufficient to close the magnetron, but if the speed of the train does not exceed the predetermined speed which is safe for the particular hazard, the opposing current is 30 insufficient to disturb the activity of the magnetron. To reopen the magnetron if the same has been closed, restoring magnetic combinations may be provided at the exit end of the restricting track section.
- 40 In Fig. 4 I show a modification of the roadside mechanism for producing protection at fixed hazards, the invention being shown as applied to the protection of curves. Between the tracks *r*, *r* near the entrant end 45 of the curve, I provide the two sets of magnets 112 and 113 each presenting the magnetic combination NS. These magnets will directly influence the magnetron *M* and if the vehicle is moving above the restrictive 50 speed, the roadside magnet combinations will impose a medium "caution" restrictive speed upon the vehicle. After passing the curve, the restoring magnet combination 114 may be provided.
- 55 While I have shown and described my apparatus in the preferred forms it will be obvious that many changes and modifications may be made in the structure disclosed without departing from the spirit of 60 the invention, defined in the following claims.
- I claim:
1. In a train control system, in combination, vehicle carried mechanism including means selectively operable for placing the train under any of a plurality of speed restrictions and an electron discharge device for controlling the operation of said means, and roadside mechanism for magnetically influencing the electron discharge device for 70 producing the controlling operations thereof.
  2. In a train control system, in combination, vehicle carried mechanism including means operable for producing a train unlimited speed effect, a restrictive speed effect, and a "stop" effect, and an electron discharge device for controlling the operation of said means to produce said effects, and roadside mechanism for magnetically 75 influencing the electron discharge device for 80 selectively producing the controlling operations thereof.
  3. In a train control system, in combination, vehicle carried mechanism including means operable for producing graduated speed restrictive effects and an electron discharge device for operating the said means, and roadside mechanism for magnetically 85 influencing the electron discharge device for 90 producing said graduated speed restrictive effects.
  4. In a train control system, in combination, vehicle carried mechanism including means operable by successive actuations for producing graduated speed restrictive effects in the progressive movement of the vehicle over a roadbed and an electron discharge device for operating the said means, and roadside mechanism for magnetically 95 influencing the electron discharge device for 100 producing the graduated speed control effects.
  5. In a train control system, in combination, vehicle carried mechanism including means operable by successive actuations for producing graduated speed restrictive effects in the progressive movement of the vehicle over a roadbed and an electron discharge device for operating the said means, and traffic controlled roadside mechanism for magnetically influencing the electron discharge device for producing the graduated speed control effects. 105
  6. In a train control system, in combination, vehicle carried mechanism including means operable by successive actuations for producing graduated speed restrictive effects and an electron discharge device for controlling the operation of said means, and roadside mechanism including a plurality of elements positioned at controlling stations on the roadside for influencing the electron discharge device to produce the successive actuations of the said means. 115
  7. In a train control system, in combination, vehicle carried mechanism including means operable by successive actuations for producing graduated speed restrictive effects and an electron discharge device for 120

- controlling the operation of said means, and roadside mechanism including a plurality of elements positioned at controlling stations on the roadside associated with a given effect, and vehicle carried manually controlled means for modifying the "stop" effect and substituting therefor a restrictive speed effect.
- 5 block thereof for influencing the electron discharge device to produce the successive actuations of the said means.
8. In a train control system, in combination, vehicle carried mechanism including 10 means operable for producing an unlimited train speed effect and for producing graduated speed restrictive effects and an electron discharge device for controlling the operation of said means to produce said effects, and roadside mechanism for magnetically influencing the electron discharge device for producing the controlling operations thereof.
9. In a train control system, in combination, vehicle carried mechanism including 20 means operable for producing an unlimited train speed effect and for producing graduated speed restrictive effects and a magnetron means for controlling the operation 25 of said means to produce said effects, and roadside mechanism for influencing the magnetron means for producing the controlling operations thereof.
10. In a train control system, in combination, vehicle carried mechanism including 30 means operable for producing an unlimited train speed effect, a plurality of graduated speed restrictive effects and a train "stop" effect and an electron discharge device for controlling the operation of said means to selectively produce any of said effects, and roadside mechanism for magnetically influencing the electron discharge device for producing the controlling operations thereof.
- 40 11. In a train control system, in combination, vehicle carried mechanism including means selectively operable for placing the train under any of a plurality of speed restrictions and an electron discharge device 45 operable directly by a magnetic field for controlling the operation of said means.
12. In a train control system, in combination, vehicle carried mechanism including means operable for producing a train 50 unlimited speed effect, a restrictive speed effect, and a "stop" effect, and an electron discharge device operable directly by a magnetic field for controlling the operation of said means to produce said effects.
- 55 13. In a train control system, in combination, vehicle carried mechanism including means operable for producing graduated speed restrictive effects and a magnetron for operating the said means.
- 60 14. In a train control system, in combination, vehicle carried mechanism including an electron discharge device operable for producing a train "stop" effect, roadside mechanism for magnetically influencing the 65 electron discharge device for producing such effect, and vehicle carried manually controlled means for modifying the "stop" effect, roadside mechanism for magnetically influencing the magnetron for producing such effect, and vehicle carried manually controlled means operable only after the train reaches a restrictive speed for modifying the "stop" effect and substituting therefor a restrictive speed effect.
15. In a train control system, in combination, vehicle carried mechanism including a magnetron operable for producing a train "stop" effect, roadside mechanism for magnetically influencing the magnetron for producing such effect, and vehicle carried manually controlled means operable only after the train reaches a restrictive speed for modifying the "stop" effect and substituting therefor a restrictive speed effect.
- 70 16. In a train control system, vehicle carried mechanism including an electron discharge device and means for producing opposed magnetic fields influencing the same, and roadside mechanism producing magnetic fields inter-reacting with the said opposed magnetic fields to produce any of three different indications in the vehicle carried mechanism.
- 80 17. In a train control system, in combination, vehicle carried mechanism including an electron discharge device and means for producing opposed magnetic fields influencing the same, and roadside mechanism including means selectively operable by traffic conditions for producing different combinations of magnetic fields for inter-reaction with the said opposed magnetic fields to selectively produce any of three different indications in the vehicle carried mechanism.
- 85 18. In a train control system, in combination, vehicle carried mechanism including means operable for placing the train under a speed restriction and an electron discharge device having opposed magnetic fields influencing the same for controlling the operation of said means, and roadside mechanism for producing magnetic fields inter-reacting with said opposed magnetic fields for producing the speed restricting operation of the electron discharge device.
- 90 19. In a train control system, in combination, vehicle carried mechanism including means selectively operable for placing the train under a speed restriction and for permitting unlimited speed thereof and an electron discharge device having opposed magnetic fields influencing the same for controlling the operation of said means and for permitting normally the unlimited speed of the train, and roadside mechanism for producing magnetic fields inter-reacting with the said opposed magnetic fields for operating the electron discharge device to effect the speed restrictive control of the train.
- 100 20. In a train control system, in combination, vehicle carried mechanism including means selectively operable for placing the train under any of a plurality of speed restrictions and an electron discharge device having means for producing opposed mag-

netic fields influencing the device for controlling the operation of said first-mentioned means, and roadside mechanism for magnetically influencing the electron discharge device to produce the controlling operations thereof.

21. In a train control system, in combination, vehicle carried mechanism including means selectively operable for placing the 10 train under a speed restriction and for permitting unlimited speed thereof and a magnetron for controlling the operation of said means, and roadside mechanism for magnetically influencing the magnetron for producing the controlling operations thereof, the said magnetron including means for producing opposed magnetic fields influencing the same and the roadside mechanism including means for producing magnetic fields 20 effective for inter-reacting with the opposed magnetic fields of the magnetron.

22. In a train control system, in combination, vehicle carried mechanism including means operable for producing graduated 25 speed restrictive effects and an electron discharge device for operating the said means, and roadside mechanism for magnetically influencing the electron discharge device for producing said graduated speed restrictive 30 effects, the said electron discharge device including means for producing opposed magnetic fields influencing the same and the roadside mechanism including means for producing magnetic fields effective for inter-reacting with the opposed magnetic fields of 35 the electron discharge device.

23. The train control combination of claim 5, in which the electron discharge device includes means for producing opposed 40 magnetic fields normally active thereon, and in which the traffic controlled roadside mechanism includes means for producing magnetic fields effective for inter-reacting with the said opposed magnetic fields.

45. 24. In a train control system, in combination, vehicle carried mechanism comprising means movable into three different positions for producing any of three different train indications and instrumentalities including 50 an electron discharge device for controlling the operation of said movable means, and roadside mechanism for magnetically influencing the said device and for operating the said instrumentalities in any of three 55 different ways for producing any of said train indications.

25. In a train control system, in combination, vehicle carried mechanism comprising means movable into three different positions 60 for producing any of three different indications and instrumentalities including a magnetron for controlling the operation of said movable means, and roadside mechanism for magnetically influencing the said magnetron 65 and for operating the said instrumentalities

in any of three different ways for producing any of said train indications.

26. In a train control system, in combination, vehicle carried mechanism comprising a brake valve magnet, a speed circuit controller, circuit means for normally energizing the magnet under "clear" conditions, for placing the same under the control of the speed controller under "caution" conditions, and for deenergizing the same under "danger" conditions, means movable into three different positions for operating said circuit means and instrumentalities including an electron discharge device for controlling the operation of said movable means, and roadside mechanism for magnetically influencing the said device and for operating said instrumentalities in any of three different ways for differently operating said circuit means. 70 80 85

27. The train control system of claim 24, in which said roadside mechanism comprises a plurality of sets of magnetic elements spaced along the roadside, each set being controllable to influence the electron discharge device in any of three different ways. 90

28. The train control system of claim 24, in which said roadside mechanism comprises a plurality of sets of magnetic elements spaced along the roadside, each set consisting of three magnets the polarities of which are changeable to produce three different combinations for differently influencing the electron discharge device. 95

29. The train control system of claim 24, in which said roadside mechanism comprises a plurality of sets of magnetic elements spaced along the roadside, each set consisting of three magnets and means whereby traffic conditions control the relative polarities of the magnets of each set. 100 105

30. The train control system of claim 24, in which said roadside mechanism comprises a plurality of sets of magnetic elements spaced along the roadside, each set consisting of a permanent magnet and two electromagnets and means for changing the polarities of the electromagnets in three different ways in response to traffic conditions. 110

31. In a train control system, in combination, vehicle carried mechanism comprising means for producing three different train indications and instrumentalities including a normally open magnetically controllable electron discharge device for controlling the operation of said means, and roadside mechanism operable for magnetically influencing the device either to close the same to produce one train indication or to close and then reopen the same to produce a different train indication or to close, open and reclose the same to produce a third train indication. 115 120 125

32. In a train control system, in combination, vehicle carried mechanism comprising means movable by successive actuations for 130

producing graduated speed restrictive effects and instrumentalities including a normally open magnetically controllable electron discharge device for actuating the said movable means, and roadside mechanism including a plurality of magnetic elements successively positioned at spaced stations along the roadbed, each for influencing the device to close and then reopen the same to produce an actuation of said movable means.

33. The train control system of claim 32, in which means is provided for controlling said magnetic elements by traffic conditions and in which the said magnetic elements operate to close and reopen the electron discharge device under "caution" traffic conditions.

34. In a train control system, in combination, vehicle carried mechanism comprising a brake controlling magnet, a speed circuit controller, a plurality of circuits for connecting the speed circuit controller and the magnet to produce graduated speed restrictive effects, means for selectively operating said circuits and instrumentalities including a normally open magnetron for operating said means, and roadside mechanism for magnetically influencing the magnetron to effect the selective operation of said means.

35. The train control system of claim 34, in which the roadside mechanism includes a plurality of sets of magnetic elements spaced along the roadside, each set influencing the magnetron to close and then reopen the same.

36. In a train control system, in combination, vehicle carried mechanism comprising a circuit controlling means movable from a given position to two other positions, instrumentalities including a normally open magnetron for controlling the operation of said circuit controlling means and for normally holding the same in the given position, and roadside mechanism for magnetically influencing the magnetron to close and reopen the same, the closing and reopening of the magnetron being effective for permitting movement of the circuit controlling means from the given to the second position and the closing of the magnetron being effective for permitting movement of the circuit controlling means to the third position.

37. In a train control system, vehicle carried mechanism comprising means movable from a given position to two other positions and instrumentalities including a normally open magnetron and means connecting the magnetron with said movable means for controlling the latter and for normally holding the same in the given position, the construction being such that the closing and reopening of the magnetron is effective for operating the connecting means to permit movement of the movable means from the given to a second position and the closing of the magnetron is effective for operating the con-

necting means to permit movement of the movable means to a third position.

38. In a train control system, vehicle carried mechanism comprising a circuit controlling means movable by increments from 70 a given position to a plurality of other positions and instrumentalities including a normally open magnetron and a means connecting the magnetron with said circuit controlling means for controlling the operation of 75 the same and for holding the same normally in the given position, the said connecting means being such that when the magnetron is closed and reopened said circuit controlling means will be moved by an increment to 80 a second position and when the magnetron is closed the circuit controlling means will be moved to a third position.

39. In a train control system, vehicle carried mechanism comprising a movable means 85 for producing different train indications, a control mechanism for effecting the movement of said means in one direction, a restoring mechanism for moving the said means in the reverse direction, a magnetically controllable electron discharge device and means connecting the electron discharge device with said control and restoring mechanisms.

40. In a train control system, vehicle carried mechanism comprising a movable means for producing different train indications, a control mechanism for effecting the movement of said means in one direction, means whereby such movement of the movable 100 means produces a train restrictive indication, a restoring mechanism for moving the said movable means in the reverse direction for producing a "proceed" indication, a magnetically controllable electron discharge device 105 and means connecting the electron discharge device with said control and restoring mechanisms.

41. In a train control system, vehicle carried mechanism comprising a movable means 110 for producing different train indications, a control mechanism for effecting the movement of said means in one direction, means whereby such movement of the movable means produces train restrictive and "stop" 115 indications, a restoring mechanism for moving the said movable means in the reverse direction for producing a "proceed" indication, a magnetically controllable electron discharge device and means connecting the 120 electron discharge device with said control and restoring mechanisms.

42. In combination with the vehicle carried mechanism of claim 39, roadside mechanism for magnetically influencing the electron discharge device to operate said control mechanism under one traffic condition and to operate the restoring mechanism under another traffic condition.

43. In combination with the vehicle car-

130

- ried mechanism of claim 41, roadside mechanism for influencing the electron discharge device for operating the control mechanism to produce either the train restrictive or "stop" indications in response to "caution" or "danger" roadside conditions respectively and to operate the restoring mechanism for producing the "proceed" indication in response to "clear" roadside conditions.
44. In a train control system, vehicle carried mechanism comprising a movable means for producing different train indications, a control mechanism for effecting the movement of said means in one direction, a 15 storing mechanism for moving the said means in the reverse direction, a normally open magnetically controllable electron discharge device and means connecting the electron discharge device with said control and 20 restoring mechanisms so that when the magnetron is subjected to a magnetic impulse to close the same the control mechanism is operated to permit movement of the movable means in one direction and when the device 25 is influenced to close and reopen the same the said control mechanism permits movement of said movable means partially in one direction and when the device is influenced to close, open and reclose the same, the 30 storing mechanism is operated to move the said movable means in the reverse direction.
45. In combination with the vehicle carried mechanism of claim 44, roadside mechanism comprising magnetic elements for influencing the electron discharge device for producing the different operations of said movable means.
46. In a train control system, roadside mechanism comprising a set of three magnetic elements having a given combination 40 of polarities and means for changing the relative condition of the elements in two different ways to provide two other combinations.
47. In a train control system, roadside mechanism comprising a set of three magnetic elements having a given combination of polarities consisting of a permanent magnet and two electromagnets and means for 50 changing the polarities of the electromagnets.
48. In a train control system, roadside mechanism comprising a set of three magnetic elements having a given combination 55 of polarities and consisting of a permanent magnet and two electromagnets and means for changing the condition of the electromagnets in three different ways in response to traffic conditions.
49. In a train control system, roadside mechanism comprising a set of three magnetic elements having a given combination of polarities and consisting of a permanent magnet and two electromagnets and means 60 whereby traffic conditions control the elec-
- tromagnets to energize the same with current of a given direction and a reverse direction.
50. In a train control system, in combination with insulated sections of track rails, 70 a set of three magnetic elements consisting of a permanent magnet and two electromagnets connected in series across the insulated rail sections.
51. In a train control system, in combination with insulated sections of track rails, 75 a set of three magnetic elements consisting of a permanent magnet and two electromagnets connected across the insulated rail sections, the electromagnets being arranged to 80 present different polarities when energized.
52. Roadside mechanism for a train control system comprising track rails subdivided into insulated blocks, each of said insulated blocks being subdivided into insulated 85 sections, a relay for each block connected across the rails at the entrant end thereof, a plurality of electromagnets wound to present opposite polarities connected across the insulated sections of a block and circuit controlling means for each block connected across the rails at the exit end thereof, the circuit controlling means of one block being controlled by the relay of the block in advance thereof. 90
53. Roadside mechanism for a train control system comprising track rails subdivided into insulated blocks, each of said insulated blocks being subdivided into insulated sections, a relay for each block connected 100 across the rails at the entrant end thereof, a plurality of electromagnets wound to present opposite polarities connected across the insulated sections of a block, a battery for each block and circuit controlling means for 105 each block connecting the battery of the block across the rails at the exit end thereof, the circuit controlling means of one block being controlled by the relay of the block in advance thereof. 110
54. Roadside mechanism for a train control system comprising track rails subdivided into insulated blocks, each of said insulated blocks being subdivided into insulated sections, a relay for each block connected 115 across the rails at the entrant end thereof, a plurality of magnets consisting of a permanent magnet and a pair of electromagnets wound to present opposite polarities connected across the insulated sections of a block, and circuit controlling means for each block connected across the rails at the exit end thereof, the circuit controlling means of one block being controlled by the means of one block being controlled by the relay of the block in advance thereof. 120
55. Roadside mechanism for a train control system comprising track rails subdivided into insulated blocks, each of said insulated blocks being subdivided into insulated sections, a relay for each block connected 125

across the rails at the entrant end thereof, a plurality of magnets consisting of a permanent magnet and a pair of electromagnets wound to present opposite polarities connected across the insulated sections of a block, the permanent magnet being located in advance of the electromagnets, and circuit controlling means for each block connected across the rails at the exit end thereof, the circuit controlling means of one block being controlled by the relay of the block in advance thereof.

5

connected across the insulated sections of a block, the permanent magnet being located in advance of the electromagnets, and circuit controlling means for each block connected across the rails at the exit end thereof, the circuit controlling means of one block being controlled by the relay of the block in advance thereof.

Signed at Niagara Falls, in the county of Niagara and State of New York, this 6th day of November, A. D. 1923.

THEODORE BODDE.
